(57) **CLAIM**

The ornamental design for a packaged ice cream display unit, as shown and described.

DESCRIPTION

FIG. 1 is a front perspective view showing my new design; FIG. 2 is a front elevational view thereof;

FIG. 3 is a right side elevational view thereof, the left side elevational view being a mirror image thereof;

FIG. 4 is a top plan view thereof;

FIG. 5 is a rear elevational view thereof; and,

FIG. 6 is a rear perspective view thereof.

The bottom view is omitted and forms no part of the claimed design. The broken lines represent environmental subject matter and form no part of the claimed design.
